(57) **CLAIM**

The ornamental design for a docking station, as shown and described.

DESCRIPTION

FIG. 1 is a perspective view of a docking station embodying the new design.

FIG. 2 is a front view of the docking station.

FIG. 3 is a rear view of the docking station.

FIG. 4 is a top view of the docking station.

FIG. 5 is a bottom view of the docking station.

FIG. 6 is a right side view of the docking station; and,

FIG. 7 is a left side view of the docking station.

The broken lines are for illustrative purposes only and form no part of the claimed design.
